THRESHOLDS

Alfred P. McEvoy and Tym F. Seay, Dallas, Tex.
Application January 13, 1956, Serial No. 558,950

5 Claims. (Cl. 20—64)

This invention relates to thresholds and more particularly to a weather strip threshold and sealing strip. This is a continuation in part of our co-pending application, Serial No. 501,229 now abandoned.

One object of the invention is to provide a new and improved threshold having a resilient weatherstrip for engaging the bottom end of a door to prevent drafts between the door and the sill.

Another object is to provide a new and improved threshold, of the type described, wherein the resilient weatherstrip is detachable and is easily assembled on the threshold after the latter is secured in place on the door sill.

Still another object of the invention is to provide a threshold having a single longitudinal groove for detachably receiving a weatherstrip.

A further object is to provide a threshold, of the type described, wherein the longitudinal groove opens upwardly and has parallel longitudinal edge portions formed by inwardly facing lips on the upper surface of the threshold, the resilient weatherstrip having longitudinal lips receivable in the longitudinal edge portions of the groove whereby the resilient strip may be detachably secured to the threshold.

A still further object is to provide a threshold, of the type described, wherein the resilient strip includes a substantially flat elongate base whose opposed edge portions constitute the longitudinal lips of the resilient weatherstrip and an elongate arcuate portion integral with the base and having its central portion arched upwardly past the lips of the threshold to engage the bottom end of a door.

Still another object is to provide a weatherstrip having an elongate base and an elongate arched portion having side edges integrally secured to the base at lines spaced inwardly from the side edges thereof, whereby the arched portion is held arched by the base.

Yet another object of the invention is to provide a weatherstrip or seal member having an elongate substantially flat relatively rigid base section and an elongate arched relatively thin flexible seal portion integrally secured to the base portion along lines spaced inwardly from the edges of said base portion, and wherein said base section may be gradually thickened in cross-section upwardly from the line of juncture of the seal portion with said base section to the center of said base section whereby said base section may be further rigidified, or wherein said base section may be gradually decreased in cross-section inwardly to permit increased flexibility along the central portion of said base section, whereby the ease with which said seal member may be positioned in and removed from a threshold or other supporting member may be controlled.

Additional objects and advantages of the invention will be readily apparent from the reading of the following description of devices constructed in accordance with the

2

invention, and reference to the accompanying drawings thereof, wherein:

Figure 1 is a perspective view showing a threshold embodying the weatherstrip in position on the sill of a door;

5 Figure 2 is an enlarged fragmentary perspective view of the weatherstrip and threshold shown in Figure 1;

Figures 2A and 2B are transverse vertical sectional views of modified forms of the weatherstrip or seal member;

10 Figure 3 is a vertical cross-sectional view of a modified form of threshold and weatherstrip seal;

Figure 4 is a vertical cross-sectional view of another form of the threshold; and,

15 Figure 5 is a fragmentary sectional view of still another form of the threshold.

Referring now particularly to Figures 1 and 2 of the drawings, the weatherstrip member 10 mounted on the threshold 11 of the door 12 includes an elongate substantially flat body or plate member 13 which is disposed on the wooden threshold 11 and is secured thereto by screws 14 which extend through suitable apertures longitudinally spaced along the center of the elongate plate or body member. The bottom surface of the body member 13 is preferably provided with elongate ridges or teeth 15 which are adapted to grip the sill 11 to fixedly hold the body member against displacement.

The body member is provided on its upper side with a longitudinal upwardly open groove 16 having lateral parallel edge portions or openings 17 and 18 formed by 30 longitudinal inwardly extending lips 19 and 20, respectively, of the body member and the flat surface 21 of the body member defining the bottom of the groove 16. The lower surface of the lips 19 and 20, of course, are spaced above the flat surface 21.

35 A resilient weatherstrip seal member 25 is removably mounted on the body member 13 and includes a substantially flat elongate relatively sized base 26 whose longitudinal edge portions or flanges 27 and 28 are receivable in the edge portions or openings 17 and 18, respectively, 40 of the groove 16. An elongate arcuate rather flexible sealing portion 30 of the weatherstrip seal member has its side edges integral with the base just inwardly of the edge portions or flanges 27 and 28 so that the upper portion of the arcuate portion 30 is positively held bowed upwardly and extends upwardly in the groove above the lips 19 and 20 of the body member 13 to engage the bottom edge of the door 12. The arcuate portion 30 is depressed downwardly by the door when the door is in closed position, insuring a substantially air tight seal between the threshold 11 and the door.

45 The side edges of the flexible sealing arcuate portion of the seal member may be thickened in cross-section as at 31 to more positively hold the arcuate portion in an upwardly projecting arched position.

The base 26 beneath the arcuate portion 30 may be flat, as shown in Figure 2, or may have its cross-sectional thickness increased gradually from the lines of juncture of the arcuate sealing portion with said base inwardly to the central longitudinal portion of said base, as shown in Figure 2A, whereby the base is more rigid and tends to resist mechanical forces acting in directions which would cause the weatherstrip seal member to be displaced from the groove. Or, if desired, the base may have its cross-sectional thickness decrease gradually from the lines of juncture toward the center, as shown in Figure 2B, so that the base may be more readily flexed along its longitudinal central portion. Such control of the thickness of the cross-section of the base provides for controlling the ease with which the seal member may be inserted in or removed from the groove of the body member.

The weatherstrip seal member may be easily positioned in place in the groove 16 of the body member by deforming or bending the base longitudinally to bring its longitudinal edge portions or flanges in proximity to one another and away from the arcuate portion 30 and then slipping these longitudinal edge portions or flanges into the edge portions or openings 17 and 18 of the groove 16. The base 26 will then abut the surface 21 of the body member.

It will be seen now that a new and improved weatherstrip has been illustrated and described which includes a plate or body member 13 having a single groove 16 in which is received a resilient weatherstrip seal member 25. It will also be seen that the sides of the body member defining the parallel vertical sides of the groove 16 may be said to be undercut to form the lips 19 and 20 and provide the groove 16 with its longitudinal edge portions or openings 17 and 18 which receive the edge portions or flanges 27 and 28 of the weatherstrip seal member, whereby the seal member is held in position on the body member.

It will also be seen that the weatherstrip and seal member are of simple forms whereby manufacture and installation of the weatherstrip assembly on a threshold or other opening are facilitated while the costs thereof are decreased.

In Figure 3 is illustrated a threshold 40 which includes an inverted elongate substantially channel-shaped member 41 having side edge portions or feet 42 and 43 which may be longitudinally grooved, as shown, to provide sharp edges whereby the threshold may be fixedly seated on a sill by means of screws, not shown, which may extend through longitudinally spaced apertures 44 provided in the channel-shaped member. A single longitudinal groove 45 is provided in the upper side of the channel-shaped member to receive a resilient weatherstrip seal member 25. A longitudinal dependent reinforcing and sealing rib 46, or flange, is formed substantially centrally of the underside of the channel-shaped member between the feet 42 and 43 and is provided with a longitudinal sharp or knife edge 47 which is sharp enough to penetrate into a wooden sill so that it effectively prevents transverse flow of air between the seal and the channel-shaped member.

A weatherstrip seal member 25 may be inserted into the groove 45 in the same manner as into the groove 16 of the body member shown in Figure 2 and will then seal between the bottom edge of a door and the channel-shaped member in the same manner.

In Figure 4 is illustrated a modified form of the threshold 40 wherein the reinforcing and sealing flange 46 is provided with a longitudinal lateral boss 50 having a downwardly opening longitudinal groove 51 for receiving the resilient bead 52 of a resilient foot seal 53 to thus secure the latter to the flange 46. The bead 52 is solid and rectangular in form and is thus positively held in place in the downwardly opening groove 51 of the base. The seal 53 may be tubular so as to readily flex into sealing engagement with the floor or sill on which the threshold is mounted.

In Figure 5 is illustrated a modified threshold 60 having a flat plate or body member 61 similar in all respects to the body member 13 of Figure 2 but having a dependent flange or bead 62 on the inner edge of each of the lips 63 which define the longitudinal side edge portions of the groove 64. The resilient weatherstrip seal member 65 is similar in all respects to the weatherstrip seal member 25 but has upstanding flanges 66 on its lateral edges which engage with the dependent flanges 62 of the body member to firmly secure the weatherstrip seal member in position on the body member 61.

It will now be seen that a weatherstrip seal member 25 has been provided which may be used with a weatherstrip or threshold body member having a single longitudi-

dinal groove and that the seal member has an arcuate flexible sealing portion 30 which extends upwardly from a substantially flat rather rigid base within the groove to engage the bottom edge of a door, window or the like.

5 It will also be seen that the weatherstrip seal member has longitudinal edge portions or flanges 27 and 28 which hold the seal member in position by engaging inwardly extending lips, such as the lips 19 and 20 of Figure 2 of the body member of the weatherstrip or threshold, the lips extending over longitudinal edge portions of the groove, and the flanges of the seal member therein.

The foregoing description of the invention is explanatory only, and changes in the details of the constructions illustrated may be made by those skilled in the art, within the scope of the appended claims, without departing from the spirit of the invention.

What is claimed and desired to be secured by Letters Patent is:

1. A combination threshold member and weather strip including: an elongate body having an upper surface formed with longitudinal marginal edge portions sloping upwardly and inwardly from said edges toward the central portion of the body and having groove means formed in its upper surface with a planar surface defining the edge portions of said groove means, said groove means including a planar bottom surface spaced below the upper surface of the body member and having a portion underlying each of the inner edge portions of the planar upper surface defining the marginal edges of the groove means and substantially rectangular openings underlying a portion of the planar upper surface of the body member adjacent the groove means, said openings being defined along their lower sides by the planar bottom surface of the groove; and a resilient sealing member having an elongate substantially flat base portion removably positioned in said groove means, said base portion having substantially rectangular longitudinally extending outwardly projecting retaining flanges disposed in the openings at each side of the groove means, the width of said base being substantially equal to the width of the planar bottom surface of the groove means; said sealing member being formed with an integral upwardly arched flexible sealing section between said flanges, said flexible sealing section projecting substantially vertically upwardly from the base portion of said sealing member to a point substantially in the plane of the planar upper surface of the body member then curving convexly inwardly above and overlying the central portion of the base portion of the sealing strip at an elevation above said planar upper surface, the outer sides of said substantially vertical portions of said flexible sealing section being disposed to engage the inner longitudinal edges of the upper surface of the body defining the groove means to be supported thereby against lateral displacement.
2. The threshold of claim 1 wherein the base portion of the sealing member is greater in cross-sectional thickness and more rigid than the arched flexible sealing section.
3. A threshold of the character set forth in claim 1 wherein the substantially vertically extending portions of the arched flexible sealing section are thicker in cross-section to resist flexing of said sealing section at the point of junction of the section with the base and to more readily permit flexing in the exposed upwardly curved portion of the planar surfaces of the body member, there being an open space between the base portion and the flexible sealing section with the base being flexible to permit insertion thereof into the groove means and removal therefrom.
4. A combination threshold member and weather strip including: an elongate body having an upper surface formed with longitudinal marginal edge portions sloping upwardly and inwardly from said edges toward the central portion of the body and having groove means formed in its upper surface with a planar surface defining

the edge portions of said groove means, said groove means including a planar bottom surface spaced below the upper surface of the body member and having a portion underlying each of the inner edge portions of the planar upper surface defining the marginal edges of the groove means and substantially rectangular openings underlying a portion of the planar upper surface of the body member adjacent the groove means, said openings being defined along their lower sides by the planar bottom surface of the groove; and a resilient sealing member having an elongate substantially flat base portion removably positioned in said groove means, said base portion having substantially rectangular longitudinally extending outwardly projecting retaining flanges disposed in the openings at each side of the groove means, the width of said base being substantially equal to the width of the planar bottom surface of the groove means; said sealing member being formed with an integral upwardly arched flexible sealing section between said flanges, said flexible sealing section projecting substantially vertically upwardly from the base portion of said sealing member to a point substantially in the plane of the planar upper surface of the body member then curving convexly inwardly above and overlying the central portion of the base portion of the sealing strip at an elevation above said planar surface, the outer sides of said substantially vertical portions of said flexible sealing section being disposed to engage the inner longitudinal edges of the upper surface of the body defining the groove means to be supported thereby against lateral displacement, the base portion of the sealing member being greater in cross-sectional thickness and more rigid than the arched flexible sealing section, the substantially vertically extending portions of the arched flexible sealing section being thicker in cross-section to resist flexing of said sealing section at the point of junction of the section with the base and to more readily permit flexing in the exposed upwardly curved portion of the planar surfaces of the body member, there being an open space between the base portion and the flexible sealing section with the base being flexible to permit insertion thereof into the groove means and removal therefrom.

5. A weather strip and support therefor including: an elongate body having an upper surface and a lower surface, said upper surface being formed with a substantially planar upper surface portion, said body having longitudinally extending groove means formed therein opening to the upper surface in the planar portion of said surface, whereby said planar portion defines the longitudinal edge portions of said groove means; said groove means having portions forming substantially rectangular openings underlying each of the inner edge portions of the planar upper surface of the body defining the marginal

edges of the groove means and having a bottom extending transversely of said body below the inner edge portions of said body defining said longitudinal edges of said groove means and continuous with the bottom surfaces of the portions of said groove means forming said substantially rectangular openings; and a resilient sealing member having an elongate base portion removably positioned in said groove means, said base portion having substantially rectangular longitudinally extending laterally outwardly projecting retaining flanges disposed in the rectangular openings at each side of the groove means, the width of said base being substantially equal to the width of the bottom of the groove means; said sealing member being formed with an integral upwardly arched flexible sealing section between said flanges, said flexible sealing section having spaced lateral portions projecting substantially vertically upwardly from the base portion of said sealing member adjacent the flanges to a point substantially in the plane of the planar upper surface of the body then curving convexly upwardly and inwardly above and overlying the central portion of the base portion of the sealing strip at an elevation above said planar surface portion of the body, there being a continuous longitudinal hollow space between said flexible sealing section and the base portion between the upwardly extending spaced lateral portions of said flexible sealing section, the outer sides of said substantially vertical portions of said flexible sealing section being disposed to engage the inner longitudinal edges of the portion of the body defining the groove means, whereby said vertical portions of the sealing section are limited against deflection laterally outwardly of said groove means, said vertical portions being flexible inwardly of said groove away from said longitudinal edges of the body defining said groove means.
